United States Patent

Des. 238,947

Patented Feb. 24, 1976

238,947

GATE VALVE BODY

Daniel R. Chilek, Rosenberg, and Floyd W. Lukens,
Alvin, Tex., assignors to ACF Industries, Incorporated,
New York, N.Y.

Filed Apr. 16, 1974, Ser. No. 461,476

Term of patent 14 years

Int. Cl. D23—01

U.S. Cl. D23—19

FIG. 1

FIG. 6

FIG. 4

FIG. 2

FIG. 3

FIG. 5

FIG. 1 is a perspective view of the gate valve body showing our new design.

FIG. 2 is a front elevation thereof.

FIG. 3 is a rear elevation thereof.

FIG. 4 is a top plan thereof.

FIG. 5 is a bottom plan thereof.

FIG. 6 is another perspective view thereof.

The broken line representation of valve actuating mechanism in FIGS. 1 through 6 is for purposes of illustration only.

We claim:

The ornamental design for a gate valve body, as shown and described.
